UNITED STATES PATENT OFFICE.

HENRY C. HIGGINS, OF WINONA, MINNESOTA, ASSIGNOR TO HIMSELF, FRED E. HIGGINS, AND HENRY M. KINNEY, ALL OF SAME PLACE.

END-GATE FOR WAGONS.

SPECIFICATION forming part of Letters Patent No. 355,528, dated January 4, 1887.

Application filed June 29, 1886. Serial No. 206,611. (No model.)

To all whom it may concern:

Be it known that I, HENRY C. HIGGINS, of Winona, in the county of Winona and State of Minnesota, have invented a new and Improved End-Gate for Wagons, of which the following is a full, clear, and exact description.

This invention relates to the construction of an end-gate for that class of wagons employed to transport grain, potatoes, and other like articles in bulk, the object of the invention being to provide a gate which may be so moved and adjusted that the wagon may be unloaded without the necessity of taking out the tie-rod; and to this end the invention consists of a gate formed in two sections, which are made so that they meet at about the transverse center of the wagon, and are united by a pivotally-connected lever and links.

Reference is to be had to the accompanying drawings, forming a part of this specification, in which similar letters of reference indicate corresponding parts in all the figures.

Figure 1 is a view of a portion of a wagon-body provided with my improved end-gate, which is represented as being closed. Fig. 2 is a similar view, wherein the gate is represented as partially open, the lower tie-rods in the two figures named being upon the outer side of the gate. Fig. 3 is a view of the gate and wagon, the gate being shown as partially opened, and the tie-rod as being upon the inner side of the gate; and Fig. 4 is a view of the gate as it appears when moved to a position to permit of its being removed from the wagon.

In the construction illustrated in the drawings, A represents the body of the wagon, which, as usual, is provided with cleats B B, between which the end-gate is held, the sides of the body being prevented from spreading by the tie-rods C and D. The end-gate E consists of the sections F, G, and H, the section F, extending entirely across the wagon-body, being held by a tie-rod, C, which passes through its cleats I I, while the sections G and H meet in the center of the body, as clearly shown.

My invention relates more particularly to the sections G and H and the attachments covered thereby, and the section F may be used or not, the use of such section depending upon the depth of the wagon-body. The section G car-

ries two brackets, J J, to which the arms of the lever K are pivoted, said lever being in Y form, and having an extending manipulating-arm, L. The section H also carries brackets, as M N, of which the bracket M is formed with 55 an upwardly-projecting arm, which serves as a support for the tie-rod D, and also acts as a stop to prevent the gate being forced inward. The brackets M N carry links O O, which are pivotally connected to said brackets, and also 60 to the arms of the lever K. Just above the arm of the lever K there is a latch, P, so mounted that it may be turned down over the arm L, as shown in Fig. 1, or be turned to clear the arm L, as shown in the other figures of the 65 drawings.

With such a gate and connections as I have just described, it will be readily understood that when it is desired to lock the gate in place the parts are placed in the position shown in 70 Fig. 1, with the lever K lying flat against the outer face of the sections G and H, the latch P being at this time turned down over the arm L. When, however, it is desired to remove the gate in order that the wagon may be unloaded, the latch P is turned up to the position shown in Fig. 2, and the arm L grasped and turned out so as to stand at about right angles to the outer face of the gate. This movement of the lever K will draw the lower 75 sections of the gate to about the position shown in Fig. 2, when by slightly raising the arm L the lower edges of the sections will be carried out clear of the bottom of the wagon, as shown in Fig. 4, after which the entire gate may be 80 readily removed.

In Fig. 3 the tie-rod D is represented as being upon the inner side of the gate; but ordinarily I prefer to place the rod as shown in the other figures.

Having thus fully described my invention, what I claim as new, and desire to secure by Letters Patent, is—

1. The combination, with a sectional end-gate, of a lever pivoted to one section, a link 95 pivoted to the other section and to the said lever, and a latch on the section to which the link is pivoted, substantially as herein shown and described.

2. In an end-gate, the combination, with a 100

section, G, carrying brackets J J, of the section H, also carrying brackets, a lever, K, links O, and a latch, P, substantially as described.

3. The combination, with a wagon-body provided with cleats B B, of an end-gate made in sections, each of which sections carries brackets, a lever pivotally connected with the brackets of one section and connected by links with

the brackets of the other section, and a latch carried by one section and arranged to engage to with the lever, substantially as described.

HENRY C. HIGGINS.
